COMBINATION PLAYING CARD AND SCORECARD HOLDER

Patrick A. Manning, Chicago, Ill.

Application March 6, 1959, Serial No. 54,883

Term of patent 7 years

(Cl. D34—5)

FIG. 6

Fig. 1 is a front elevational view of a combination playing card and scorecard holder embodying my new design; Fig. 2 is a rear elevational view;

Fig. 3 is a side elevational view thereof as seen from the left hand side of Fig. 2;

Fig. 4 is a top plan view of the same;

Fig. 5 is a side elevational view as seen from the right side of Fig. 2; and

Fig. 6 is a perspective view of the same.

I claim:

The ornamental design for a combination playing card and scorecard holder, substantially as shown.
